CLAIM

The ornamental design for a novelty snowman, as shown and described.

DESCRIPTION

FIG. 1 is a perspective view of a novelty snowman showing my new design;

FIG. 2 is a front elevation view thereof;

FIG. 3 is a right side elevation view thereof;

FIG. 4 is a left side elevation view thereof;

FIG. 5 is a rear elevation view thereof; and,

FIG. 6 is a bottom plan view thereof.

The broken lines shown in the drawings represent portions of the novelty snowman that form no part of the claimed design. All surfaces not shown form no part of the claimed design.
